CLAIM

The ornamental design for liquid storage tank with tool compartment, as shown and described.

DESCRIPTION

FIG. 1 is an exploded perspective view of a liquid storage tank with tool compartment showing my new design with the mounting shank shown in an extended position; FIG. 2 is a left side elevational view thereof with the mounting shank recessed; the right side elevational view being a mirror image thereof;

FIG. 3 is a rear elevational view thereof;

FIG. 4 is a front elevational view thereof;

FIG. 5 is a top plan view thereof; and,

FIG. 6 is a bottom plan view thereof.

FIGS. 2-6 are shown in reduced scale.
